UNITED STATES PATENT OFFICE.

ROBERT B. GOODYEAR, OF PHILADELPHIA, PENNSYLVANIA, ASSIGNOR OF
ONE-HALF TO JACOB HOFFMAN, OF SAME PLACE.

SHEDDING MECHANISM FOR LOOMS.

SPECIFICATION forming part of Letters Patent No. 431,346, dated July 1, 1890.

Application filed February 26, 1890. Serial No. 341,860. (No model.)

To all whom it may concern:

Be it known that I, ROBERT B. GOODYEAR, a citizen of the United States, and a resident of Philadelphia, in the county of Philadelphia and State of Pennsylvania, have invented certain new and useful Improvements in Sheding Mechanisms for Looms; and I do hereby declare the following to be a full, clear, and exact description of the invention, such as will enable others skilled in the art to which it appertains to make and use the same.

My invention relates to improvements in shedding mechanisms for looms; and the object of my invention is to improve the means for shifting the heddles with a view to promoting simplicity of construction and to lock or confine the heddle-lever in place when the heddle is in either a raised or lowered position.

My invention consists in the combination of devices and peculiar construction, arrangement, and adaptation of parts, as will be hereinafter fully described, and particularly pointed out in the claims.

In the accompanying drawings I have only shown as much of a loom-frame and heddle as will enable others skilled in the art to understand the same, in which drawings—

Figure 1 is a side elevation showing a part of a heddle, a loom-frame, and my improved means for operating the heddle, the heddle-lever being shown in its lowered position. Fig. 2 is a detail view, partly in section, showing the heddle-lever in its raised position and resting firmly in a seat of the fixed abutment and in contact with the movable abutment. Fig. 3 is an end view illustrating a series of heddle-levers, the means for operating the same, the pattern-cylinder, and the operating mechanism for the latter. Fig. 4 is a detail view, on an enlarged scale, of the operating mechanism for the pattern-cylinder. Fig. 5 is a detail view of a part of the frame for the shedding mechanism.

Like numerals of reference denote corresponding parts in all the figures of the drawings.

The numeral 1 designates a part of a frame of a loom, 2 the crank-shaft, 3 a heddle, and 4 an endwise-movable or reciprocating jack,

all of which parts are common to the ordinary loom and do not require more detailed description in this specification.

5 designates one of the side pieces of a frame in which the shedding mechanism is supported, which frame is composed of two corresponding pieces similar to the piece 5, which frame-pieces project outward from the loom-frame, as indicated in Fig. 1. In the lower part of the frame-piece 5, I provide two 60 vertical parallel slots 6 6', and in these slots are arranged reciprocating lifter and depressor bars 7 7'. To one of these bars is connected a link 8, which link is connected to and operated by the crank-shaft 2, and said vertically movable lifter and depressor bars are carried by vertical slides 9 9', which are fitted in suitable guides on the frame-piece 5, said slides being connected for simultaneous operation by links 11 11' to an oscillating lever 70 12, which is fulcrumed at its middle.

No novelty is claimed in the devices just described, as they are common features in looms; but I will now proceed to describe my improvements more specifically.

15 designates the heddle-lever of my improved shedding mechanism for looms, which lever is capable of an endwise movement within certain limits, as well as a turning or oscillating movement. The heddle-lever is 80 arranged in an upright inclined position, and the said lever is guided between the abutments, which will be presently described, and the guide-posts 16 17, which are arranged parallel with each other, but out of line vertically, as shown in Fig. 1, and fixed to the side piece 5 of the supporting-frame. The lever is arranged in contact with the guide-post so as to slide freely between the same, and at the same time it is capable of turning or rocking a limited distance in order to turn from the approximately horizontal raised position of Fig. 2 to the more upright position shown in Fig. 1, and the said lever is prevented from lateral displacement by the fixed plate or strip 85 18, which is fitted on and secured to the guide-posts. (See Figs. 1 and 2.) The lower end or heel 19 of the heddle-lever is enlarged and rounded, and to the center of this rounded heel is connected the upper end of the ver- 90 95 100

tically-movable jack 4 by means of a pivot-bolt 19', the said heddle-lever being capable of turning or rocking a limited distance on the said bolt or fulcrum as said lever is moved 5 up or down by the jack and elevator-slides in shifting the heddle. The enlarged rounded end of the heddle-lever plays between the two abutments 20 21, one of which 20 is fixed or rigid with the frame-piece 5, while the other 10 abutment 21 is movable laterally for a limited distance toward and from the fixed abutment 20 in order to permit the enlarged end of the heddle-lever to clear the seats in the fixed abutment and move in a vertical direction 15 between said abutments. The fixed abutment 20 is provided in its lateral face adjacent to the heddle-lever with the seats 20' 20", to receive a part or segment of the rounded heel of the said heddle-lever, said seats being situated at the upper and lower ends of the fixed abutment. The movable abutment is situated at one side of the fixed abutment, substantially parallel with the same, and at a sufficient distance from the fixed abutment 20 to permit the heel of the heddle-lever to fit snugly between said abutments when said lever is lowered. The movable abutment is pivoted at its lower end to the frame-piece 5, as at 22, and it has a lateral arm 23, to which 30 is connected a coiled retracting-spring 24, which operates to hold the movable abutment normally in contact with said heddle-lever when said lever is either raised or lowered, the abutment being movable laterally of the 35 heddle-lever when the heel of the lever impinges against the abutment. The movable abutment 21 is thus controlled by its spring, and at its lower end it has a seat 21', against which the heel of the heddle-lever impinges 40 when said lever is lowered.

The upper end of the heddle-lever is provided with two apertures 25 25', and through one of these apertures 25 is passed and secured a cord 26, which runs over a guide-pulley 26' and is connected to the upper side of the heddle 3. Through the other aperture 25' is passed and secured another heddle-cord 27, which runs over the upper guide-pulley 27' and the two lower guide-pulleys 28, situated below the heddle and pulley 27', as shown, and the said cord 27 is then connected to the lower side of the heddle 3. (See Fig. 1.) The heddle-cords are drawn taut between the heddle and heddle-lever, and said cords hold 55 the heel of the lever 15 firmly against one or the other of the seats of the fixed abutment, so that the said lever is locked or confined in place. Thus when the heddle is raised the heddle-lever is lowered, as indicated in Fig. 60 1, and its hub is in contact with the seats 21' and 20" of the movable and fixed abutments, and as the heddle-lever is pulled by the heddle-cord 26 it is obvious that the heel of the heddle-lever is forced firmly against the seat 20" of the fixed abutment and the seat 21' of the movable abutment and the heddle-lever is prevented from movement. When the

heddle is lowered, the heddle-lever is raised to the position indicated in Fig. 2, the post 17 serving as the fulcrum on which the lever turns, and the heel of said lever bears on the seat 20' of the fixed abutment, and as the cord 27 pulls on the upper end of the heddle-lever the heel of the said lever is forced into the seat 20' of said abutment by the strain or pull of the heddle-cord 26, as is obvious.

30 designates the pattern-cylinder, which is carried by a shaft 31, suitably journaled in the frame-piece 5, and this cylinder has rows of perforations 32 formed in its surface to receive the pins 33, which pins act to lift the weighted end of a lever 35, or a series of such levers. (See Fig. 3.) The lever 35 is fulcrumed on a pin or shaft 36, fixed in the frame-piece 5, and said lever has a depending curved arm 36', the free end of which arm has a guide or loop 37, which loop receives the vertically-movable jack, which jack is free to slide in the loop, whereby the lever 35 is operated by the pattern-cylinder, 85 and it serves to shift the lever at the desired intervals, so that its arm 36' moves the jack on the bolt 19' in position to be engaged by the lifter-bar or depressor-bar or slide, for the purpose well known in this art. On the other end of the shaft 31 a ratchet-wheel 37' is fixed, and on this end of the shaft is loosely fitted a bell-crank lever 38, one arm of which carries a gravity-pawl 39, and to the other arm of which is connected a pitman 40, which leads to the operating-lever 12, whereby the lever 12 operates the bell-crank lever through the pitman to cause the gravity-pawl to engage the ratchet-wheel at regular intervals, and thus rotate the pattern-cylinder at each oscillation of the 90 lever 12 and each movement of the bars 7 7', which are operated by the crank-shaft.

The operation of my invention may be briefly stated, as follows: As the crank-shaft rotates, the lifter and depressor bars are 110 raised and lowered alternately, and the lever 12 operates the pawl 39 to rotate the pattern-cylinder, so that the weighted lever 35 is moved by the pins of the pattern-cylinder at suitable intervals to shift the jack, so that 115 the notches or shoulders of the latter are engaged by the bars at the desired intervals, and the heddle-lever is raised or lowered to move the heddle. As the heddle-lever is raised the movable abutment yields laterally 120 to the enlarged heel of the said lever and permits the lever to turn as it is raised, and thus assume the position shown in Fig. 2, in which position the heel of the lever is forced into the seat 20' of the fixed abutment and locked 125 or confined in place by the strain of the cords and the contact of the heel of the heddle-lever with the seat 20' of the fixed abutment. When the lever is drawn down, it slides through the guide-posts and between the 130 abutments, the post 17 serving as the fulcrum on which the lever turns and the movable abutment yielding to permit the enlarged heel to pass the same and to rest firmly in the

seat 21' of the movable abutment and the seat 20" of the fixed abutment, in which position the lever is locked or confined in place by the pull or strain of the heddle-cords on 5 said heddle-lever.

Although I have described my invention as adapted for use in connection with a single heddle-lever, it is obvious that a series of such levers can be provided and used in connection with the fixed and movable abutments and the pattern-cylinder, which heddle-levers are arranged between the guide-posts and separated from each other by the plates 18.

15 Changes in the form and proportion of parts and details of construction can be made without departing from the spirit or sacrificing the advantages of my invention, and I therefore reserve the right to make such modifications as fairly fall within the scope of my invention.

Having thus fully described my invention, what I claim as new, and desire to secure by Letters Patent, is—

25 1. The combination, with a heddle, of an endwise-movable rocking heddle-lever connected by intermediate cords with the heddle, a jack pivoted to the heddle-lever, means for operating the jack, and the abutments between which the heddle-lever slides, the abutments having the seats to receive the heel of the heddle-lever when in its elevated and depressed positions, substantially as described.

35 2. The combination, with a heddle, of an endwise-movable rocking heddle-lever connected by intermediate cords with the heddle, the guide-posts arranged on opposite sides of the heddle-lever, a jack pivoted to the heddle-lever, means for operating said jack, and the 40 abutments provided with the seats, substantially as specified, for receiving the heel of the heddle-lever, substantially as described.

3. The combination, with a heddle, a jack,

and means for operating the jack, of an endwise-movable heddle-lever pivoted to the jack 45 and connected to the heddle by intermediate cords, a fixed abutment arranged laterally of the heddle-lever and having the seats to receive one end of said lever in its raised and lowered positions, and a movable abutment 50 arranged on the other side of said heddle-lever, to move laterally of the same for a limited distance and likewise having a seat for the heddle-lever, substantially as described.

4. The combination, with a heddle, a jack, 55 and mechanism for operating the jack, of an endwise-movable heddle-lever having its enlarged heel pivoted to the jack and connected to the heddle by intermediate cords, the fixed guide-posts between which the heddle-lever is fitted, a fixed abutment having the seats for the enlarged heel of the heddle-lever, and a movable spring-pressed abutment arranged on the other side of the heddle-lever and also having a seat, substantially 60 as described.

5. The combination of the lifter and depressor bars, the slide-bars secured to the lifter and depressor bars, an oscillating centrally-pivoted lever linked to the slide-bars, 70 a pattern-cylinder carried by a shaft having a ratchet-wheel, a bell-crank lever fitted on the pattern-cylinder shaft and linked to the oscillating lever and carrying a gravity-pawl, a heddle-lever, a jack, and a weighted lever 75 35, having a depending arm which is connected to the jack by a loop or guide in which the jack is free to move vertically, substantially as described.

In testimony whereof I affix my signature in 80 presence of two witnesses.

ROBT. B. GOODYEAR.
